SPREADER AND DISPENSER OF BOBBY PINS

Ralph P. Sharp, Sr., Carville, La.

Application September 10, 1941, Serial No. 410,350

6 Claims.

(Cl. 132—1)

This invention is a device for feeding bobby pins such as are customarily used to hold the hair in place and is particularly advantageous for use in beauty parlors or other places where a plurality of pins must be rapidly applied.

An object of the invention is to provide a bobby pin feeder which feeds a spread bobby pin to the hair to grip the same in proper position.

A further object of the invention is to provide a device of this character which is actuated by one hand of the operator, leaving the other hand free to arrange the hair for receiving the pin.

Another object of the invention is to provide a bobby pin feeder and spreader in which the spread pin is fed to the hair and automatically released thereon to hold the hair as desired.

Of equal importance with the foregoing objects, the invention includes a magazine capable of holding a substantial number of bobby pins so that the operator will have sufficient pins to take care of the requirements of the most exacting hair style without having to stop and reload the device.

The device meets a very serious condition which exists at the present time and is particularly to be found in beauty parlors where large numbers of bobby pins are applied daily. It is customary for the operator to pry the legs of the pin apart either with the fingernail or by means of the teeth, and it is well known that such expedients are both dangerous and unsanitary. Devices in the nature of spreaders have been proposed but these are objectionable, because, it is necessary to hold each pin manually in spread condition to apply them to the hair. This is a slow operation, because the pins must be applied individually and, also dangerous since, being of spring metal, they are quite frequently accidentally released and stab the flesh of the operator.

The construction of the present invention includes a magazine for holding a suitable number of bobby pins, means for automatically feeding the pins one at a time to an ejector member which is operated by the finger of one hand of the operator. This ejector member moves the pin into contact with a spreader device whereby the legs of the pin are spread as the pin is ejected so that it may be positioned properly upon the hair. The continued movement of the ejector device causes the spreader member to release the pin and permit the legs to spring together to properly grip and hold the hair.

Referring to the drawings:

Figure 1 is a top plan view showing the ejector member in retracted position;

Figure 2 is a back plan view showing the ejector member in retracted position;

Figure 3 is an end elevation of the device;

Figure 4 is a detailed view, partly in section, showing the ejector member about to engage a pin in the magazine and taken on line 4—4 of Figure 1;

Figure 5 is a similar view showing the pin engaged by both the ejector and spreader devices and the pin in spread and in partly ejected position;

Figure 6 is a top plan view showing the ejector member at the limit of its ejecting movement about to release a pin from the device;

Figure 7 is a sectional view on the line 7—7 of Figure 1;

Figure 8 is a sectional view on the line 8—8 of Figure 1;

Figure 9 is a sectional view showing the pivotal mounting of the spreader and releasing member;

Figure 10 is a sectional view showing the spreader and releasing member in its releasing position;

Figure 11 is a section on the line 11—11 of Figure 9;

Figure 12 is a perspective view of the spreader and releasing member; and

Figure 13 is a section on the line 13—13 of Figure 3.

The device may be made of any desired material, preferably metal or plastic, of a total weight such that it may be readily manipulated by one hand of an operator and by a single finger of that hand without unduly tiring the operator. Referring to Figure 1, the construction includes a magazine 10, the edges of which are provided with overturned guide flanges 11 and the body wall 12 of which is slotted as shown at

40 13 to provide a guide for an automatic feeding device in the form of a spring pressed pressure shoe 14. This pressure shoe, as shown in Figure 7, has a lug 15, which extends through the slot, and a suitable retaining member 16 connected thereto whereby the pressure shoe is held in position to slide in said slot to automatically feed the bobby pins in position to be engaged by the ejector device. The automatic feeding of the pressure shoe is produced in any suitable manner.

For instance, in the form shown in Figure 3, the retaining member 16 has attached to it one end of a cord 17 which is carried around a suitable spool 18 and the opposite end thereof is attached thereto. The spool is rotatably mounted upon a shaft 19 carried by and fixed

to spaced lugs 20 at one edge of the back plate, as shown in Figures 3 and 7. A suitable coil spring 21 is positioned upon the fixed shaft 19, one end being secured thereto and the other end being secured to the spool 18 which is rotatably mounted on the shaft. When it is desired to load the magazine, the operator pulls the retaining member and with it the shoe out of the slot 13 and positions the shoe in a pair of spaced bracket members 22 on the outside face of the body wall 12, as shown in Figure 2, where it is resiliently held during the loading. The magazine is loaded by positioning a card upon which the bobby pins are usually sold against the free open end of the magazine and simply pushing the pins into the same, so that their ends are positioned beneath the overturned flanges 11. When in this position, the flat sides *f* of the pins engage the wall 12 of the magazine and preferably the longer leg *l* is on the bottom, i. e. in contact with the wall 12. Thereafter, the operator removes the shoe from the brackets and engages the same with the said rear wall 12 of the magazine, so that the shoe and retaining member are on opposite sides of the magazine wall with the shoe engaging and resiliently pressing the edge of the outermost bobby pin, as shown in Figures 1 and 6. In this position, the pins are resiliently held and pressed upwardly towards the ejector end of the device (to be described next) by reason of the resilient force of the spring 21, above described.

Referring to Figure 7, the wall of the magazine at its upper end terminates in a wall 12' of a block 23 which extends at right angles to the wall 12 and forms a guide against which the pins to be ejected are successively positioned by the spring pressed plunger shoe 14. The block 23 is of a length substantially greater than the width of the magazine, as shown in Figures 1 and 6, and carries the ejector and spreader means which will now be described.

On its outer or exposed surface, the block is provided with a longitudinally extending guide slot or groove 24 and, at one end, the said block is provided with a longitudinally extending elongated recess 25, as shown in Figures 3 and 9. The ejector device indicated as a whole at E carries a finger loop 26 to which is connected a pair of parallel spaced arms 27, which at their free end are connected to the ejector foot 28. This ejector foot and the finger ring 26, connect the ends of the spaced parallel arms 27 and hold them fixed in proper spaced relation for a purpose which will be later described. This spaced relation is such, that the arms will slide freely upon and be guided by the upstanding block 23 to cause the ejector device contact surface 29 to always engage the closed end of a bobby pin bearing against the upstanding wall surface 12', as shown in Figures 1 and 7. The inner arm 27, i. e. the one adjacent the magazine, terminates in or carries the said ejector device contact surface 29. The ejector foot 28 is provided with an upstanding portion 30 which, in the rearward movement of the ejector device, serves to limit its travel by engagement with a stop 31 in the form of a band through which the legs 27 may freely slide and be guided, the said band being connected by welding or otherwise to the upstanding block 23 in any suitable manner. In this connection, a pair of finger grip rings 32 may likewise be secured to the upstanding block 23 in any suitable manner and, are positioned to extend so that they may be conveniently gripped

in two of the fingers of one hand while another finger of that hand or the thumb operates the ejector device and slides the same back and forth by engaging the finger ring 26. That is, the ring members 32 are positioned clear of the sliding movement of the ejector device under the action of the finger ring 26. In the forward movement of the ejector device, one of the arms 27, preferably the outer one or the one other than that carrying the pin engaging contact surface 29, has an inwardly extending guide flange 33 which engages in the groove 24 in the block and is guided thereby, as shown in Figure 13.

From the foregoing description, it will be observed that pins are automatically positioned against the inner surface of the block 23, namely against the smooth upstanding wall surface 12' thereof, where they are successively engaged by the ejector contact surface 29 of the ejector device E when the latter is moved forwardly by the finger. When a pin is moved forward by the ejector device, as stated above, it is also simultaneously spread and the means for accomplishing this will now be set forth. Pivotally disposed in the recess 25 in the block 23 is a spreader member indicated as a whole at S and shown in detail in Figure 12. This spreader member has a body 34 and includes on one side thereof a cam surface 35 adapted to be engaged by the ejector foot on the outer arm 27 in its ejecting movement and, on the opposite side, has a pin spreading cam or wedge 36, the lower part of which is, as shown in Figures 11 and 12, slightly undercut to a depth somewhat in excess of the thickness of the metal of the usual bobby pin and which is disposed in the path of the movement of the pin as it is being ejected by the ejector device. The spreader member is pivotally held in the recess 25 by the pivot pin 37, and is resiliently positioned in the path of movement of a pin ejected by the ejector device, as shown in Figures 4 and 5, by means of a wire spring 38, which bears by one end against the outer edge of the pivotally mounted spreader member and has its other end connected to the upper surface of the block 23 as by a pin 39, as shown in Figure 3. By reason of this construction, as a pin is fed forward, it is simultaneously spread while it is being ejected by reason of the legs of the pin engaging and being spread by the cam surface 36, as shown in Figure 5. As the ejector device continues its forward movement, the leg 27 which carries the guide flange 33 engages the cam surface 35 of the pivotally mounted spreader member, whereby the latter is caused to pivot upon the pin 37 and move outwardly out of the path of the ejecting movement of the bobby pin, as shown in Figure 10, to release the pin in position upon the hair. It is to be noted that the cam surface 35 projects outwardly from the upstanding block 23 a sufficient distance so that the outer leg 27 will always engage the same to automatically release the pin at the limit of movement of the ejecting device.

Upon return of the ejector member to retracted position, as shown in Figure 1, the plunger shoe 14 moves another pin into ejecting position against the wall 12' automatically in readiness for the next ejection and, at the same time, the spreader member is returned to its normal position with the wedge 36 in the path of ejecting movement of a bobby pin, as shown in Figure 9, by reason of the action of the spring 38. In this connection, it will be noted that the spring 38 causes the side edge 40 of the spreader member 75 to engage an upstanding wall 41 formed integral

with and extending at right angles to the adjacent magazine guide flange 11. The laterally extended portion 42 of the magazine wall 12, in cooperation with the wall 41 which extends at right angles thereto, provide a mouth M. This mouth has side walls 40 and 41 and a bottom 42 through which the pins are successively released when the spreader member is pivoted outwardly, as shown in Figures 1, 6, 9, 10 and 11.

In the operation of the device, the operator, as heretofore described, places a card of bobby pins adjacent the free end of the magazine with the flat sides disposed so that they will lay upon the plate 12 and with the longer flat side in engagement therewith, in such a manner that the ends of the pins are received beneath the flanges 11 of the magazine and with the closed ends positioned under the flange to the left, as shown in Figure 8. Thereupon, the pressure shoe is removed from the retaining brackets 22 so that it will operate in the slot 13 to slidably and resiliently engage the supply of pins in the magazine. When the pins are loaded in the magazine, they lie edge to edge with the first pin to be ejected bearing against the inner surface 12' of the upstanding block 23, as shown in Figures 1, 6 and 7. The ejector member is in retracted position, as shown in Figures 1 and 2, and the operator then grips the device, placing two fingers in the rings 32 and another finger or thumb of the same hand in the finger ring 26. The operator has the other hand entirely free to work upon the hair which is advantageous and, as heretofore stated, the present device is of such light weight that it may be operated without inconveniencing the operator or causing discomfort to the person whose hair is being dressed. The operator now positions the device adjacent the head and moves the ejector device forward by movement of the finger engaging in the ring 26. This causes the ejector device contact surface 29 to engage the closed end of the pin to be ejected, as shown in Figure 4 and, as the ejector device moves forward, the free ends of the pin move in a path to engage the wedge 36 by which they are spread as the ejector device moves the pin forwardly, as shown in Figure 5. The ejector device continues its forward movement at the same time spreading the pin upon the hair and when the front end of the outer arm 27 engages the cam surface 35, and the ejector device continues to move, the spreader device is rocked outwardly on its pivot 37, as shown in Figure 10, and the pin is released through the mouth M by the ejector device as the ejector device reaches the limit of its forward movement and the spreader member moves completely out of the path to allow the pin to clear the mouth. This ejection of the pin from the device takes place with a spring-like action due to the fact that up to this point, the legs of the pin have been spread and when the spreader device moves completely out of the path of the pin being ejected, and the ejector device is at the limit of its forward ejecting movement, whereby the pin is released, the resilient action of the legs in springing together causes the pin to leave the mouth under a slight force which, at all times, will assure that the pins will not become clogged in the mouth of the device but will be released cleanly upon the hair. This is of considerable importance in that it insures that the operator may quickly manipulate the device to apply the pins without fear of having the pins catch in the

device or pull the hair and thereby discomfort the patron being treated.

The operator now retracts the ejector device, another pin is positioned automatically against the wall 12' in readiness to be ejected, and simultaneously the spreader member is automatically returned to its spreading position in the path of ejection of the pin and with its edge 40 in engagement with the upstanding wall 41 of the mouth M. The operation may thus be repeated to automatically and constantly feed spread pins to the hair until the supply of pins is exhausted and, as will be appreciated, any suitable number of pins may be carried in the magazine.

While it is customary for beauty parlors and hairdressing salons to obtain their bobby pins on a card from which they may be readily fed to the magazine of the present device, as heretofore described, it is not, of course, difficult to insert pins individually in the magazine. In some cases, the bobby pins are collected by the beauty shops and, by reason of this device, they need not be wasted, as the device opens all pins the same distance without damage to the pins, such as springing or bending. The pins can therefore be used over and over again in perfect shape.

It will be observed that the construction includes a magazine with means for automatically feeding pins therefrom, as well as means for ejecting a spread pin. The construction not only provides for ejecting a spread pin but for releasing the same upon the hair and, it is to be observed, that the ejector device and the spreader device operate simultaneously to eject and spread the pin, and the operator retains perfect control of the pin during the entire operation.

I claim:

1. A bobby pin feeder comprising a magazine, means for feeding pins therefrom, means for ejecting a spread pin, and finger grip rings associated with the magazine and the ejecting means, whereby the feeder can be actuated by one hand of the operator.

2. A bobby pin feeder comprising a magazine, means for feeding pins therefrom, means for ejecting a spread pin and releasing the same in engagement with the hair, and finger grip rings associated with the magazine and the ejecting means, whereby the feeder can be actuated by one hand of the operator.

3. A bobby pin feeder comprising a magazine, means for feeding pins therefrom, and means for ejecting a spread pin, said last named means comprising an ejector device and a spreader device simultaneously operating to eject and spread the pin, and finger grip rings associated with the magazine and the ejector device, whereby the feeder can be actuated by one hand of the operator.

4. A bobby pin feeder comprising a magazine, means for feeding pins therefrom, and means for ejecting a spread pin, said last named means comprising an ejector device and a spreader device simultaneously operating to eject and spread the pin, said spreader device being movably mounted to release the pin at the limit of its movement by the ejector device, and finger grip rings associated with the magazine and the ejector device, whereby the feeder can be actuated by one hand of the operator.

5. A bobby pin feeder comprising a magazine, means for feeding pins therefrom, and means for ejecting a spread pin, said last named means comprising an ejector device and a spreader device simultaneously operating to eject

and spread the pin, means for moving the ejector device, said spreader device being movably mounted, said ejector device engaging the spreader device to move the same and release a pin, and finger grip rings associated with the magazine and the ejector device, whereby the feeder can be actuated by one hand of the operator.

6. A bobby pin feeder comprising a magazine, means for feeding pins therefrom, and means for ejecting a spread pin, said feeder being adapted to be held in one hand and said means being manually operable by movement of a single finger of that hand.

RALPH P. SHARP, Sr.
